UNITED STATES PATENT OFFICE.

GIOVANNI EMANUELE ELIA, OF NEW YORK, N. Y.

SHIP.

1,286,261.

Specification of Letters Patent.

Patented Dec. 3, 1918.

Application filed March 17, 1916. Serial No. 84,947.

To all whom it may concern:

Be it known that I, GIOVANNI E. ELIA, a subject of the King of Italy, residing at Hotel Ritz-Carlton, New York, N. Y., have 5 invented certain new and useful Improvements in Ships; and I do hereby declare the following to be a full, clear, and exact description of the invention, such as will enable others skilled in the art to which it applies 10 pertains to make and use the same.

This invention relates to ships, especially war-ships, of the kind in which compartments or chambers situated along the sides of the ship's hull are provided with a number 15 of strong wire cables which offer a flexible resistance to the expansion of the gases resulting from the explosion of a mine or torpedo contiguous to the ship and thus serve to diminish the destructive force of the explosion. 20

According to this invention the wire cables are connected to the transverse bulkheads of the compartments or chambers and to the framing of the ship by members which 25 are adapted to be sheared when the cables are placed under great tension as a result of the expansion of the explosion gases. Each end of each of the cables may have one or more shearing members or one end of the 30 cable may be permanently attached to the bulkhead or other fixed part while the other end is provided with one or more of the shearing members. In the preferred construction each end of the cable has a number 35 of shearing members constituted by a number of collars or projections on the periphery of a sleeve which is connected to the cable and is disposed within a bracket attached to the bulkhead or framing and having an internal flange 40 against which the innermost collar bears. The collars are made of softer material than the flange on the bracket so that when the cable is placed under severe tension as a result of a mine or torpedo explosion, the collars will be sheared in succession by the said flange. 45

In order that the said invention may be clearly understood and readily carried into effect I will describe the same more fully 50 with reference to the accompanying drawings, in which:—

Figure 1 is a transverse section of part of a battleship provided with my improvements;

55 Figs. 2, 3, 4, 5, 6 and 7 are enlarged views of parts thereof;

Fig. 8 is a front elevation showing the arrangement of the flexible members constructed according to my invention applied to a ship having double bulkheads. 60

Fig. 9 is a corresponding view to Fig. 8 showing the position of the parts after the flexible members of one compartment or chamber have been subjected to the effect of an explosion. 65

As shown in Fig. 1 the outer wall of the chamber A comprises thin plating B supported by light framings b suitably connected at their upper and lower ends to the adjacent portions of the ship. The inner 70 wall of the chamber A comprises a strong concave bulkhead C. Within the chamber A is an arrangement of cables D located in vertical and horizontal rows and connected at their points of crossing by wires or the like 75 d. Each cable is provided at its ends with a number of shearing members constituted by a number of collars e on a sleeve E which is connected to the cable and is disposed within a bracket F attached to the bulkhead 80 or framing C. The said bracket F has an internal flange f against which the innermost collar e bears.

In order that this arrangement may act effectively the bracket may be mounted on 85 trunnions g supported on a bifurcated member H attached to the ship's framing or the transverse bulkheads so that it can follow the movements of the cable when the latter is bent by the force of an explosion, thereby 90 insuring that the axis of the aforesaid sleeve will always be in line with the cable and thus obviate danger of the cable becoming broken where it engages with the sleeve. As shown in the drawings the brackets or the vertical 95 cables may be connected to the ship's framing and those of the horizontal cables to the transverse bulkheads that separate the various compartments along the ship.

The approximate position assumed by the 100 collars after an explosion is illustrated at Figs. 6 and 7. In Fig. 6 the lower collar e' is shown as having been sheared by the explosion while in Fig. 7 two of the collars e are assumed to have been sheared.

105 It has been found that when wire cables or other flexible, deformable or breakable members are connected to the transverse bulkheads, the tension on the said members of one compartment, resulting from the explosion gases, is liable to break or deform the bulkheads, so that sea water enters not 110

only the particular compartment directly affected by the mine or torpedo explosion, but also the compartments on each side of this compartment. In order to avoid this 5 disadvantage, I arrange the bulkheads in duplicate as shown at Figs. 8 and 9, the flexible members D of one compartment being connected to one of these bulkheads G and the members of the other compartment to 10 the contiguous bulkhead G¹. Owing to this arrangement and as illustrated at Fig. 9, even if the two inner bulkheads G of a compartment are broken or deformed the other bulkheads G¹ are not affected. This arrangement of bulkheads is particularly, although 15 not exclusively, applicable to the above described wire cables and shearing members.

What I claim and desire to secure by Letters Patent of the United States is:

20 1. A warship or other sea going vessel having compartments around the ship for the purpose of protecting it from the effects of submarine explosions, means located within said compartments which offer a 25 flexible resistance to the expansion of the gases resulting from an explosion contiguous to the ship, and means for attaching said first mentioned means to the framing of the ship, said last mentioned means being adapted to be sheared when the first 30 mentioned means are placed under great tension as a result of the expansion of the explosion gases.

2. A warship or other sea going vessel 35 having compartments around the ship for the purpose of protecting it from the effects of submarine explosions, flexible members located within said compartments, and members for attaching said flexible members to the ship, said attaching members being adapted to be sheared when the flexible 40 members are placed under great tension as a result of the expansion of the explosion gases.

45 3. A warship or other sea going vessel having compartments around the ship for the purpose of protecting it from the effects of submarine explosions, wire cables located within said compartments, and members for attaching said wire cables to the framing of the ship, said members being adapted to be sheared when the cables are placed under great tension as a result of 50 the expansion of the explosion gases.

55 4. A warship or other sea going vessel having compartments around the ship for the purpose of protecting it from the effects of submarine explosions, flexible members located within said compartments, and 60 members at both ends of said flexible members for attaching the latter to the fram-

ing of the ship, said members being adapted to be sheared when the flexible members are placed under great tension as a result of the expansion of the explosion gases.

65 5. A warship or other sea going vessel having compartments around the ship for the purpose of protecting it from the effects of submarine explosions, flexible cables located within said compartments and shearing members for attaching the ends of said cables to the ship's framing comprising brackets attached to the ship's framing, each bracket having an internal flange, sleeves connected to the ends of said cables 70 and disposed within said brackets, and collars on each of said sleeves, the innermost collar bearing on said internal flange.

6. A warship or other sea going vessel 80 having compartments around the ship for the purpose of protecting it from the effects of submarine explosions, flexible cables located within said compartments and shearing members for attaching the ends of said cables to the ship's framing comprising 85 brackets attached to the ship's framing, each bracket having an internal flange, sleeves connected to the ends of said cables and disposed within said brackets, and collars made of softer metal than the said 90 flange on each of said sleeves, the innermost collar bearing on said internal flange.

7. A warship or other sea going vessel 95 having compartments around the ship for the purpose of protecting it from the effects of submarine explosions, flexible cables located within said compartments, shearing members for attaching the ends of said cables to the ship's framing, supporting 100 brackets for the shearing members, and trunnions for the supporting brackets so that the latter can follow the movements of the cables when the latter are bent by the force of the explosion.

8. A warship or other sea going vessel 105 having compartments around the ship for the purpose of protecting it from the effects of submarine explosions, transverse bulkheads within said compartments said transverse bulkheads being arranged in duplicate, and means located within said compartments which offer a flexible resistance to the 110 expansion of the gases resulting from an explosion contiguous to the ship, said means within one compartment being attached to one of said duplicate transverse bulkheads and to the framing of the ship, and said means within the adjacent compartment being attached to the contiguous transverse bulkhead and to the framing of the ship.

120 In testimony whereof I affix my signature.
GIOVANNI EMANUELE ELIA.
